UNITED STATES PATENT OFFICE.

EMMI COURT, OF LAKOTA, NORTH DAKOTA.

COMBINATION-TOOL.

1,360,891.

Specification of Letters Patent.

Patented Nov. 30, 1920.

Application filed June 1, 1918. Serial No. 237,769.

To all whom it may concern:

Be it known that I, EMMI COURT, a citizen of the United States, residing at Lakota, in the county of Nelson and State of North Dakota, have invented certain new and useful Improvements in Combination-Tools, of which the following is a specification.

My present invention relates to combination tools, and consists in the improvement 10 of a convenient tool which is simple, strong and durable, and is capable of being put to many uses.

The primary object of my invention is to provide such a tool embodying upon a single member, a drill, a wrench, a pipe wrench, 15 a pair of calipers, a hatchet, a hammer, a soldering tool, a marker, and in fact many other household necessities too numerous to mention.

20 A further object of my invention is to insure a rigid connection of the tools with the shank, and at the same time to enable the convenient assemblage and detachment thereof without requiring any complicated 25 adjustment of the parts.

Having these and other objects of general utility and design in view, I have illustrated a preferred embodiment of my invention in the accompanying drawings, in which:—

30 Figure 1 is an assembled elevation of my combination tool;

Fig. 2 is a top plan view;

Fig. 3 is a fragmental under plan of the tool as shown in Fig. 1;

35 Fig. 4 is an elevation similar to Fig. 1, showing the assembling of a drill chuck to the spindle;

Fig. 5 is a section on line 5—5 of Fig. 4;

Fig. 6 is a section on line 6—6 of Fig. 4;

40 Fig. 7 is a detail of the end of the spindle adapted to receive the chuck;

Fig. 8 is a section on line 8—8 of Fig. 1;

Fig. 9 is a dissembled view of the body or shank of my tool;

45 Fig. 10 is a view of a section of the shank shown with a hammer head secured thereto;

Fig. 11 is a view corresponding to Fig. 10, showing a hatchet head in place of the hammer;

50 Fig. 12 is a fragmentary detail of the opposite end of the shank shown assembled to a marker;

Fig. 13 is a view taken at right angles to Fig. 12; and

55 Fig. 14 is a detail of the same end of the shank embodying a soldering iron.

Similar reference characters refer respectively to similar parts throughout the several views.

My tool comprises a rectangular shank or 60 bar 15 (Fig. 9) one end 15^a of which is provided with a plurality of spaced apertures 16, 17 and 18; the other end terminates in a stationary serrated jaw 19, having an aperture 20 adjacent the base thereof for the 65 reception of a pin to pivotally support a movable jaw to be hereinafter described.

Tools such as a hammer 21, hatchet 22, or wrench jaw 23, are fastened to the bar 15 by means of a suitable bolt 24, passing 70 therethrough as shown. A bracket 25 may be rigidly secured to the shank at 18, having journaled thereto a beveled gear 26 meshing with a driving gear 27, keyed to a threaded spindle 28. A wrench jaw 29 is slidably 75 mounted upon the shank 15 and has an aperture therethrough, through which spindle 28 passes, and a set-screw 30 extends into said aperture and engages the threads on the spindle, so that as the spindle is rotated the 80 jaw 29 will be brought to or separated from the jaw 23.

When it is desired to assemble a drill, the bracket 25 is slidably mounted on the shank, the spindle 28 brought through an aperture 85 in the jaw 23, and a drill chuck 31 mounted thereon (Figs. 4-7).

A toothed jaw 32 coacting with the jaw 19, may be pivoted at 20 for the assembling of a plier or pipe wrench, and caliper arms 90 33—33 may be mounted on the outer ends of these jaws 19 and 32, as shown in Fig. 1, an adjusting screw 34 passing through the respective jaws.

A marker 35 may be secured to the jaw 95 19 in a similar manner; or a soldering iron 36 may be gripped between the jaws 32 and 19, as shown in Fig. 14.

It will thus be apparent to those skilled in the art to which my invention appertains, 100 that the shank 15 is capable of carrying practically any character of tool, but for the sake of brevity I have shown and described only a few specific tools.

What I claim is:—

105 In a tool of the character described, a bar, a stationary tool part fixed at one end of said bar, a movable tool part slidable on the bar, a bracket slidable on said bar behind the movable tool part, means to adjustably lock said bracket on the bar, an operating member for said movable tool carried

by said bracket and movable tool part, both of said tool parts being adapted to receive said operating member therethrough, means for actuating said operating member, and 5 means carried by said movable tool part for operative engagement with the operating member.

In testimony that I claim the foregoing

as my own I have hereto affixed my signature in the presence of two subscribing witnesses. 10

EMMI COURT.
